CLAIM

The ornamental design for a watch band as shown and described.

DESCRIPTION

FIG. 1 is a perspective view of watch band showing my new design;

FIG. 2 is a front view thereof;

FIG. 3 is a rear view thereof; and,

FIG. 4 is a right side view thereof.

The broken lines in the drawings represent portions of the watch band and form no part of the claimed design. The other broken lines in FIG. 1 showing a device represent environmental subject matter only and form no part of the claimed design.

1 Claim, 4 Drawing Sheets(56)
